BOOKHOLDER

Ernest Kopp, Brooklyn, N. Y.

Application December 29, 1944, Serial No. 570,275

11 Claims. (Cl. 45—80)

1

This invention relates to new and useful improvements in book holders.

More particularly, the invention proposes an improved book holder which is characterized by a base and a book supporting member pivotally mounted on said base and extending upwards and rearwards and intended to support a book.

Furthermore, it is proposed to adjustably mount a wedge on said base to engage the back of said book supporting member for holding the latter in selected inclined positions.

Still further it is proposed that said wedge engage rack teeth on the back of said member for securely holding it in inclined positions, as desired.

The invention also proposes using more than one wedge for more securely holding the book supporting member.

Another object of the invention is the construction of a device as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure—

Fig. 1 is a perspective view of a book holder constructed in accordance with this invention.

Fig. 2 is a side elevational view of Fig. 1.

Fig. 3 is a back view of Fig. 1.

Fig. 4 is a fragmentary enlarged vertical sectional view taken on the line 4—4 of Fig. 3.

Fig. 5 is a fragmentary vertical sectional view taken on the line 5—5 of Fig. 4.

Fig. 6 is a back view similar to Fig. 3 but illustrating a book holder constructed in accordance with a modified form of this invention.

Fig. 7 is a side elevational view of a book holder constructed in accordance with another modification of this invention.

Fig. 8 is a back view of the book holder of Fig. 7.

Fig. 9 is a back view similar to Fig. 8 but illustrating the parts in a different position.

Fig. 10 is a fragmentary enlarged sectional view taken on the line 10—10 of Fig. 9.

The book holder illustrated in Figs. 1—5 inclusive, includes a base 11 for resting on a table or other flat object. A book supporting member 12 is pivotally mounted on the front edge of said base 11 with hinges 13. The book supporting

2

member 12 extends upwards and rearwards. A rack 14 is mounted upon the back or underside of the book supporting member 12. At the bottom the book supporting member 12 is provided with a ledge 15 against which a book may be rested.

A wedge 16 is adjustably mounted on the base 11 and engages said rack 14 for holding said book supporting member 12 in selected inclined positions. The top end of the rack 14 has a large downwardly projecting tooth 14' engageable with additional rack teeth 16' formed along the inclined front edge of the wedge 16 for holding the book supporting member 12 in additional inclined positions. More specifically, the wedge 16 engages into a groove 17 formed in the top face of the base 11. The bottom wall of the groove 17 is formed with rack teeth 18 which are engaged by complementary rack teeth formed on the bottom of said wedge 16. Resilient means is connected with the bottom of said wedge 16 and is so arranged as to engage the rack teeth upon the bottom of the wedge 16 with said rack teeth 18.

25 The resilient means referred to in the previous paragraph is in the nature of a leaf spring 20 which is disposed within the groove 21 formed in the bottom face of the base 11. Several supporting elements 22, such as headed nails, or screws are mounted upon the bottom of the wedge 16 and support the spring 20. These nails or screws 22 pass through a slot 23 formed in the base 11. The spring 20 has a low central portion and has its ends engaging the top wall of said groove 21. The wedge 16 has handles 25 by which it may be moved.

The operation of the book holder is as follows: A book may be rested on the book supporting member 12 so that it engages against the ledge 15. When it is desired to change the angle of the book supporting member 12 it is necessary that the book supporting member 12 be first pivoted upwards. Then the wedge 16 may be adjusted forwards or rearwards on the base 11. To do this the handles 25 are manually gripped and moved upwards to slightly lift the wedge 16. This disengages the teeth on the bottom of the wedge 16 from the teeth 18. Now the wedge 16 may be moved forwards or rearwards. Then the book supporting member 12 is rested on the wedge 16 in its newly adjusted position. The top apex of said wedge 16 will engage different ones of the teeth of the rack 14 and so hold the book supporting member 12 in a new inclined position or

the tooth 14' will engage the rack teeth 16' for this purpose.

In Fig. 6 another form of the invention is shown which is similar to the prior form, distinguishing merely in the fact that the book supporting member 12 is provided with a pair of racks 14 mounted along its edge portions. These racks 14 are engaged by a pair of wedges 16 which are mounted along the edge portions of the base 11. Each wedge 16 is similarly adjustably mounted on the base 11. The wedges 16 are connected by a rod 26. Handles 27 project from the sides of the wedges 16 by which they may be adjusted in unison.

In other respects this form of the invention is similar to that previously shown and like reference numerals identify like parts in each of the several views.

In Figs. 7-10 still another form of the invention has been shown which distinguishes from the prior forms in the fact that the book supporting member 12 is provided with a central rack 14 and with side racks 14'. In other words, there are three racks on the back of said member 12. A platform 30 is adjustably mounted upon the base 11. This platform 30 has rack-like teeth 31 projecting from its bottom face and engaging in slots 32 formed along said base 11. These slots 32 are formed with complementary rack teeth 33 normally engaged by the rack teeth 31. Each rack 31 is urged downwards by a leaf spring 34 supported by several headed screws or nails 35. These screws or nails 35 pass through slots 36 formed in the base 11. Each leaf spring 34 is disposed in a slot 37 formed in the bottom face of the base 11.

Transverse yoke-like guide rods 38 are mounted upon the platform 30. A pair of wedges 40 with rack teeth 16' are transversely adjustably mounted on the yokes 38. In their spread positions, these wedges 40 are engaged with the side racks 14, as illustrated in Fig. 8. However, the wedges 40 may be moved together so as to be centrally located as illustrated in Fig. 9, and now they are cooperative with the central rack 14. The platform 30 has side projections 41.

The operation of this form of the invention is similar to the prior forms, except for the fact that there is a choice of supporting the book supporting member 12 along its center, or along its edges. However, it is necessary that the platform 30 be adjusted forwards and rearwards on the base 11 to adjust the longitudinal positions of the wedges 40 and so control the tilt of the book supporting member 12. The platform 30 has said side projecting portions 41 which may be used as handles by which the platform 30 may be initially raised to disengage the rack teeth 31 and 33 and then may be moved forwards and rearwards.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A book holder, comprising a base, a book supporting member pivotally mounted on said base and extending rearwards and upwards, a rack on the back of said member, and a wedge adjustably mounted on said base and engaging said rack for holding said book supporting mem-

ber in a selected inclined position, said rack having a top projecting tooth larger than any of its other teeth, engageable with rack teeth formed on the inclined side of said wedge.

5. 2. A book holder, comprising a base, a book supporting member pivotally mounted on said base and extending rearwards and upwards, a rack on the back of said member, a wedge adjustably mounted on said base and engaging said 10 rack for holding said book supporting member in a selected inclined position, said wedge engaging in a groove in said base, said rack having a top projecting tooth, larger than any of its other teeth, engageable with rack teeth formed on the inclined side of said wedge.

3. A book holder, comprising a base, a book supporting member pivotally mounted on said base and extending rearwards and upwards, a rack on the back of said member, a wedge adjustably mounted on said base and engaging said 20 rack for holding said book supporting member in a selected inclined position, said wedge engaging in a groove in said base, and rack teeth formed in said groove and engaged by rack teeth on the 25 bottom of said wedge, said member rack having a top projecting tooth, larger than any of its other teeth, engageable with rack teeth formed on the inclined side of said wedge.

4. A book holder, comprising a base, a book 30 supporting member pivotally mounted on said base and extending rearwards and upwards, a rack on the back of said member, a wedge adjustably mounted on said base and engaging said rack for holding said book supporting member 35 in a selected inclined position, said wedge engaging in a groove in said base, rack teeth formed in said groove and engaged by rack teeth on the bottom of said wedge, and resilient means urging said wedge downwards against said rack teeth, 40 said member rack having a top projecting tooth, larger than any of its other teeth, engageable with rack teeth formed on the inclined side of said wedge.

5. A book holder, comprising a base, a book 45 supporting member pivotally mounted on said base and extending rearwards and upwards, racks on the back of said member, and wedges adjustably mounted on said base and engaging said racks for holding said book supporting member in selected inclined positions, said member racks each having a top projecting tooth, larger than any of its other teeth, engageable with rack teeth formed on the inclined sides of said wedges.

6. A book holder, comprising a base, a book 55 supporting member pivotally mounted on said base and extending rearwards and upwards, racks on the back of said member, and wedges adjustably mounted on said base and engaging said racks for holding said book supporting member in selected inclined positions, said wedges being transversely adjustably mounted on a platform, racks upon the bottom of said platform engaging longitudinally extending grooves in said base, complementary rack teeth in said grooves, and resilient means for engaging the racks of said platform with said last-mentioned racks.

7. A book holder, comprising a base, a book 70 supporting member pivotally mounted on said base and extending rearwards and upwards, a rack on the back of said member, a wedge adjustably mounted on said base and engaging said rack for holding said book supporting member in a selected inclined position, said wedges being 75 transversely adjustably mounted on a platform,

racks upon the bottom of said platform engaging longitudinally extending grooves in said base, complementary rack teeth in said grooves, and resilient means for engaging the racks of said platform with said last-mentioned racks, and yoke-like guide members mounted on said platform and transversely adjustably supporting said wedges.

8. A book holder comprising a base, a book support hinged at its bottom to the front of said base and extending upwardly and rearwardly therefrom, said support having a rack extending transversely along its under face, said rack having its top tooth formed larger than its other teeth, a wedge disposed between said base and support and having a top face inclined upwardly and rearwardly and provided with rack teeth for coacting with said large tooth, and means for adjustably disposing said wedge in different transverse positions on said base including rack teeth on said base and cooperating rack teeth connected to said wedge.

9. A book holder comprising a base, a book support hinged at its bottom to the front of said base and extending upwardly and rearwardly therefrom, said support having a rack extending transversely along its under face, said rack having its top tooth formed larger than its other teeth, a wedge disposed between said base and support and having a top face inclined upwardly and rearwardly and provided with rack teeth for coacting with said large tooth, and means for adjustably disposing said wedge in different transverse positions on said base including rack teeth on said base and cooperating rack teeth connected to said wedge and resilient means urging said last mentioned rack teeth together.

10. A book holder comprising a base having two transversely extending racks in its upper face, a book support hinged at its bottom to the front of said base and extending upwardly and rearwardly therefrom, said support having a middle rack and a rack on each side thereof extending transversely along its under face, said support racks each having its top tooth formed larger than its other teeth, two wedges disposed between

said base and support and having a top face inclined upwardly and rearwardly and provided with rack teeth for coacting with said large teeth, and means for adjustably disposing said wedge in different transverse and different longitudinal positions on said base including rack teeth connected to said wedges for coaction with said base racks.

11. A book holder comprising a base having two transversely extending racks in its upper face, a book support hinged at its bottom to the front of said base and extending upwardly and rearwardly therefrom, said support having a middle rack and a rack on each side thereof extending transversely along its under face, said support racks each having its top tooth formed larger than its other teeth, two wedges disposed between said base and support and having a top face inclined upwardly and rearwardly and provided with rack teeth for coacting with said large teeth, and means for adjustably disposing said wedge in different transverse and different longitudinal positions on said base including rack teeth connected to said wedges for coaction with said base racks, and resilient means urging said last mentioned rack teeth together.
